UNITED STATES PATENT OFFICE.

BENJAMIN H. DOWNER, OF BUFFALO, AND CHARLES A. BEACH, OF ALBANY,
NEW YORK.

CAR-COUPING.

SPECIFICATION forming part of Letters Patent No. 311,730, dated February 3, 1885.

Application filed August 15, 1884. (No model.)

To all whom it may concern:

Be it known that we, BENJAMIN H. DOWNER, of Buffalo, in the county of Erie and State of New York, and CHARLES A. BEACH, of Albany, in the county of Albany and State of New York, have invented new and useful Improvements in Car-Couplings, of which the following, taken in connection with the accompanying drawings, is a full, clear, and exact 5 description.

This invention relates to that class of car-couplings in which hooks connected to the ends of the cars are arranged to interlock with each other. Heretofore said coupling-hooks were 15 arranged in a horizontal plane, so as to project from the side of the coupling-bar, and the latter was arranged to vibrate laterally or sidewise. Such couplings, however, are defective and objectionable in several respects—viz., 20 the pivotal connection of the coupling bar or hook with the car does not possess the required stability and durability; to effect the automatic coupling of the hooks requires heavy springs to resist the side thrust of the hooks, and in 25 case one of said springs is broken the utility of the coupling is destroyed. Furthermore, coupling-hooks which are disposed in a horizontal plane and interlock sidewise are liable to be thrown out of engagement by a sudden 30 side sway or lurch of the car, and aside from these defects such car-couplers are complicated and expensive.

The object of this invention is to provide an automatic car-coupling which shall be simple 35 and comparatively inexpensive in construction, efficient, safe, and durable in operation, capable of coupling cars of different heights, and possess the requisite strength for resisting the strain it is subjected to, and also the convenience of readily removing the coupling-bar 40 from the draw-bar, when desired, for repairs and renewal or exchange for others; and the invention consists in the novel construction and combination of parts, as hereinafter fully 45 explained, and specifically set forth in the claims.

Figures I^a and I^b are longitudinal sections of our improved car-coupling, showing the same in an uncoupled and a coupled position 50 and with the draw-bar in line with each other.

Figs. I and II are side views of the same, illustrating its capability for coupling cars of different heights. Fig. III is a plan view of one of the draw-bars provided with our coupling. Fig. IV is an end view. Fig. V is a detached 55 isometric view of the coupling-bar, and Fig. VI is an isometric view of a modification of the coupling-bar adapted to be used in connection with the ordinary coupling link and pin.

Similar letters of reference indicate corresponding parts.

A represents the draw-bar or bumper, connected to the car in any suitable and well-known manner. The outer end or head of the 65 draw-bar is formed with two vertical jaws, B B, which have on their inner side vertical grooves a a, closed at their lower end by a stop, b.

C denotes the coupling-bar, formed with 70 hooks n n, which are disposed in a vertical plane, and preferably harpoon-shaped. The sides of the coupling-bar are provided with cheek-pieces c c, fitted to slide in the grooves a a of the jaws B B. The coupling-bar thus has 75 a secure hold on the draw-bar, and while braced in a horizontal position, so as to effectually prevent vertical oscillation of said coupling-bar, at the same time is allowed to slide freely vertically to accommodate itself to the elevation of the coupling-bar of the approaching car 80 to be coupled.

In the operation of coupling the cars the hook end of one coupling-bar slides over the top of the beveled end of the other coupling-bar, and is thus lifted until the hooked portions n n thereof become interlocked, as illustrated in Fig. II of the drawings, in which position they are retained by the gravity of the overlying coupling-bar.

In order to make ample allowance for the variations in the heights of the cars we make the projections of the cheek-pieces c above and below the coupling-bar of unequal heights, so that by reversing the coupling-bar in its connection with the draw-bar the former becomes supported at a greater or less elevation, and thus adapted to couple with the coupling-bar 95 of a car of greater or less height.

To guard against the thrust of the coupling-

- bar out of the draw-bar we secure to the top of the draw-bar a spring-plate, *s*, which has its free end extending over the coupling-bar, and in order to admit of removing the coupling-bar from the draw-bar when required we fasten the spring-plate *s* by bolts *e*, passing through a longitudinal slot, *d*, in the spring-plate, so that by loosening the bolt said plate can be shifted to liberate the coupling-bar.
- 10 To the top of the coupling-bar we attach a yoke, *f*, and the latter we connect with a lever, *L*, pivoted on the end of the car, as shown in Fig. IV of the drawings, by means of which lever the coupling-bar can be lifted to effect the uncoupling. Said lever is extended across the car, so as to be accessible from either side of the car, and thus obviate the necessity of the train-man entering between the cars.
- 15 When it becomes necessary to use our improved car-coupling in connection with the ordinary coupling pin and link, we substitute for the harpoon-shaped coupling-bar a perforated plate provided with the cheek-pieces *c c*, as illustrated in Fig. VI of the drawings.
- 20 We do not claim, broadly, a car-coupling composed of interlocking coupling-hooks, as we are aware the same is not new; but
- 25 We do claim specifically as our improvements—
- 30 1. The combination, with the draw-bar or bumper, of a coupling-hook disposed in a vertical plane, and connected with the draw-bar to slide vertically thereon, and braced in a horizontal position, substantially as set forth.
- 35 2. The combination of the draw-bar provided with vertical grooves and the coupling-hook disposed in a vertical plane, as shown, provided with cheek-pieces adapted to slide in said grooves, substantially as set forth.
- 40 3. The combination of the draw-bar provided with vertical grooves, the coupling-bar formed with cheek-pieces adapted to slide in said

grooves, and having harpoon-shaped coupling-hooks disposed in a vertical plane, as shown, a stop across the lower end of the grooves, and a spring-guard over the coupling-hook adapted to arrest the upward thrust of the coupling-bar out of the draw-bar, substantially as described and shown.

4. The combination of the draw-bar *A*, having vertical jaws *B B*, provided on their inner side with vertical grooves *aa*, and with a stop, *b*, at the lower end of said grooves, the coupling-bar *C*, formed with cheek-pieces *c*, fitted movably in the grooves *a*, said coupling-bar having harpoon-shaped coupling-hooks standing in a vertical plane, and the spring *s*, secured to the top of the draw-bar, and having its free end extended over the space between the jaws *B B*, substantially as described and shown.

5. In combination with the draw-bar *A*, provided with the vertical jaws *B B*, and the coupling-hook *C*, sliding vertically between said jaws, the spring *s*, applied to the top of the draw-bar, and provided with the slot *d*, and the bolt *e*, passing through said slot, whereby the spring can be shifted to release the coupling-hook, substantially as set forth.

In testimony whereof we have hereunto signed our names and affixed our seals, in the presence of two attesting witnesses, at Buffalo and Syracuse, respectively, in the counties of Erie and Onondaga, in the State of New York, this 24th day of July, 1884, and this 29th day of July, 1884.
